United States Patent Office

Des. 203,823
Patented Feb. 22, 1966

203,823

ROTATABLE OUTLET BOX

William E. Kelly, Jersey City, N.J., assignor to The Thomas & Betts Co., Incorporated, Elizabeth, N.J., a corporation of New Jersey

Filed July 9, 1964, Ser. No. 80,787

Term of patent 14 years

(Cl. D26—1)

Fig. 1

Fig. 2

Fig. 3

Fig. 4

FIGURE 1 is a top plan view of a rotatable outlet box, showing my new design;

FIGURE 2 is a front elevational view, the rear being substantially a mirror image thereof;

FIGURE 3 is an end elevational view, the opposite end being substantially a mirror image thereof; and

FIGURE 4 is a bottom plan view thereof.

I claim:

The ornamental design for a rotatable outlet box, as shown and described.
